UNITED STATES PATENT OFFICE.

CHARLES HERMANN WAECHTER, OF NEW YORK, N. Y.

ATTACHMENT FOR PLUMBING FIXTURES.

Application filed January 26, 1924. Serial No. 688,748.

To all whom it may concern:

Be it known that I, CHARLES HERMANN WAECHTER, a citizen of the United States, residing in New York, county of New York, and State of New York, have invented certain new and useful Improvements in Attachments for Plumbing Fixtures, of which the following is a specification.

This invention relates to attachments for plumbing fixtures and more especially to a device for controlling discharge from bath tubs and the like.

The purpose of my invention is the production of a device which will be readily attachable to any plumbing fixture without the use of tools and without changes in the fixture, which will provide means for controlling the rate of discharge and the height of water within the fixture while effectually preventing air suction and vortices primarily the cause of the discharge noises particularly objectionable in dwellings.

It is my particular object to provide an attachment for the overflows of bath tubs permitting the user to control the overflow level therein and enjoy the benefits of such water level as may best suit his convenience and physique while assuring that the outflowing liquid discharge will be silent and of minimum quantity for the maintenance of solutions of constant density when bathing preparations are employed.

Certain other improvements accomplished by my invention will be apparent from the following description of one embodiment thereof.

Like numerals have been employed to indicate like parts throughout the several views. In the drawings—

Figure 1 is a front elevation of a preferred embodiment of my invention.

Figure 2 is a cross section of Figure 1, taken upon line 2—2,

Figure 3 illustrates an application of my invention to a standard bath tub and shows the device of Figure 1 cross-sectioned in vertical plane as upon line 3—3.

Referring particularly to Figures 1 and 2, a member 5, having a back 7, sides 9, and a curved end 10, forms what is for all practical purposes, a three-sided box, one end (10) of which is closed and the other end of which is open. This opening is rectangular in outline, the edge 14 supplying a weir for the discharging water as will be described. Sides 9 and the end 10 are pref-

erably provided at their edges with an insert of packing material 15, for water-tight abutment against the interior surface of the bath tub in such manner that this surface 60 forms the fourth side of the box as shown in Figure 3.

The interior surfaces of bath tubs are usually of porcelain like smoothness and of extreme hardness, and drilling the fixture 65 without chipping this surface in a destructive manner is practically impossible. Engagement of the other fittings of the tub, such as faucets 20, to retain an attachment involves ungainly structures not universally adaptable to all installations.

Attachment of my device is secured without the foregoing difficulties by the employment of vacuum cups 22, preferably of rubber. Cups 22 are secured to a cross 75 bar 24 by such means as the studs 26. This cross bar 24 is provided with openings slidably engaging the studs 28 which are attached to the back 7 of box member 5. For adjustment of the relation between the vacuum cups and the member 5, and to compress packing 15 for the formation of a water-tight joint with the tub surface, a thumb screw 30 is threaded into the bar 24 and bears upon back 7.

In use the cups 22 are moistened and then pressed against the inner surface 32 excluding the air from the spaces 34. The pressure of the surrounding atmosphere then holds the cups to the tub surface. Thus to 80 apply the device to a bath tub the user merely places it over the waste opening 35 of the bath tub and presses the cross bar 24 causing the suction cups 22 to grip the tub surface. He then turns thumbscrew 30 95 until it bears on back 7 and thus compresses the packing 15. The device is now in working position. It will be understood that the tub may be engaged at any height with reference to the waste opening 35 and that the 100 water level in the tub will be controlled by the height of edge 14, as all discharge to the opening 35 must be over this edge. Edge 14 therefore forms a weir for the discharging water spreading it into a thin sheet entering the opening at right angles to its axis.

Since the water has no rotary motion it tends to cling to the lower surface of the waste pipe, vortices and indrawing of air is prevented, thus effectually removing the 110 cause of most plumbing noise.

Manifestly with my invention applied a

much higher water level may be maintained in the bath tub and this level may be as much higher than the normal overflow level as one desires.

- 5 Many changes and modifications are possible in the structure and in the parts of my invention with the accomplishment of beneficial results, all within the spirit of my invention and within the scope of the app-
10 pended claims as will be understood by those skilled in the art. While my invention has been particularly described as suited to bath tubs, it will be clear that it is equally suited to other plumbing fixtures and while it has
15 been shown as applied to the overflow waste opening, it will be apparent that it can be equally well applied to other openings with the accomplishment of improved results.

What I claim is:

- 20 1. In a device for adjusting overflow level in a bath tub, a box member covering the bath tub overflow opening and adjustable means for retaining said member at the desired height respective thereto, said means
25 including suction cups attaching members engaging the interior surface of the tub.
2. In an overflow attachment for bath tubs having waste openings in substantially vertical plane, a box member having an open side and end, adjustable suction means for securing said member over the waste opening with its open side in registry therewith and with its open end upward.
30 3. An adjustable overflow attachment for plumbing fixtures comprising a three-sided
35

member having an open end, the edges of said member being provided with flexible means conforming to the interior fixture surface surrounding a waste opening, the open end of said attachment forming an inner 40 overflow orifice, and suction cups secured to one side of the said attachment being adapted to position the attachment at any desired height.

4. In an overflow attachment for bath 45 tubs a waste pipe extension comprising a hollow member having an open side and a waste inlet gasket, means secured to the side edges of said member, suction cups engaging the tub surface, a cross bar connecting 50 said cups and means engaging said member and cross bar to support the aforesaid member with the waste inlet uppermost and with its open side against the tub surface over the waste pipe opening.

5. In a discharge attachment for bath tubs a member of substantially rectangular cross section having a semicircular closed end, a substantially straight open end, three closed sides and an open side, suction means for 55 engaging the tub surface, adjustable means for simultaneously engaging the suction means and one of the closed sides of said member to secure said member over the bath tub discharge opening for the control 60 thereof.

In testimony whereof I have affixed my signature to this specification.

CHARLES HERMANN WAECHTER.
